(57) **CLAIM**

The ornamental design for a dialysis catheter tip, substantially as shown and described.

DESCRIPTION

FIG. 1 is a perspective view of a catheter tip.

FIG. 2 is an enlarged perspective view of the catheter tip illustrated in FIG. 1.

FIG. 3 is an enlarged top plan view of the catheter tip illustrated in FIG. 1.

FIG. 4 is an enlarged side elevation view of the catheter tip illustrated in FIG. 1.

FIG. 5 is an enlarged bottom plan view of the catheter tip illustrated in FIG. 1; and,

FIG. 6 is an enlarged end view of the catheter tip illustrated in FIG. 1.

The broken line showing of portions of the dialysis catheter tip illustrates portions of the dialysis catheter tip which form no part of the claimed design. The broken line showing of the catheter illustrates the environment of the claimed design and forms no part thereof.

1 Claim, 3 Drawing Sheets
